Merchaut and Kilgore

UNITED STATES PATENT OFFICE.

MERRILL J. HIRE, OF MINNEAPOLIS, MINNESOTA, ASSIGNOR TO PLAYGROUND & GYMNASIUM EQUIPMENT COMPANY, OF MINNEAPOLIS, MINNESOTA, A CORPORATION OF MINNESOTA.

BOB ROCKER.

Application filed April 9, 1927. Serial No. 182,513.

My present invention has for its object to provide a bob rocker for the exercise and amusement of children, and to this end it consists of the novel devices and combinations of 5 devices hereinafter described and defined in the claims.

In the accompanying drawings, which illustrate the invention, like characters indicate like parts throughout the several views.

10 Referring to the drawings:

Fig. 1 is a side elevation of the bob rocker;

Fig. 2 is a view in transverse vertical section taken on the line 2—2 of Fig. 1, on an enlarged scale, with some parts broken away; 15 and

Fig. 3 is a fragmentary view partly in side elevation and partly in longitudinal vertical section taken on the line 3—3 of Fig. 2.

The bob rocker, as shown, comprises rocker- 20 equipped end members 4, a seat board 5, and a tie member in the form of a foot rack 6, which members, board, and tie member are in the form of a parallelogram.

Each end member 4 comprises a pair of lat- 25 erally spaced rockers 7, to the longitudinal centers of which is rigidly secured and suitably braced a pair of upright posts 8 that are rigidly connected at their vertical centers by a crosstie bar 9. Said posts 8, of each pair, 30 are further connected by upper, lower and intermediate crosstie steel rods 10, 11 and 12. The upper crosstie rods 10 afford handles by which the end members 4 may be rocked.

The seat board 5 is provided with depend- 35 ing pairs of oilless wood bearings 13 rigidly bolted thereto and journaled on the crosstie rods 12. These bearings 13 extend into notches 14 in the upper edge portions of the crosstie bars 9 and hold the seat board 5 40 against edgewise shifting movement on the crosstie rods 12.

Stop blocks 15 are bolted to the inner faces 45 of the crosstie bars 9 and are provided with flat oblique upper surfaces 16 arranged to engage the under side of the seat board 5 to limit the rocking movement of the end members 4.

The foot rack 6, as shown, comprises a pair 50 of longitudinally extended bars 17 and spaced foot-engaging bars 18 bolted to the bars 17. The longitudinal bars 17 are provided with bores through which the crosstie rods 11 extend to support the foot rack 6 therefrom.

The ends of the longitudinal bars 17 are split to their bores and provided with bolts which hold said ends frictionally clamped onto the crosstie rods 11 and thus prevent the foot rack 6 from shifting edgewise on said crosstie rods. The crosstie rods 11 are free to turn in the seats provided therefor in the posts 8. 55

By reference to Fig. 2 it will be noted that the seat board 5 is considerably narrower than the foot rack 6 so that children sitting astride said board may rest their feet on the crosstie bars 18 of the foot rest 6. 60

Children sitting on the seat board 5 next to the end members 4 with their feet engaging the foot rack 6 will grasp the handles 10 and impart rocking motion to said end members by means of arm and leg movements. The 70 children sitting on the intermediate portion of the seat board 5 with their feet resting on the foot rack 6 will assist in imparting rocking movements to the end members by means of leg movement. As the seat board 5 and foot 75 rack 6 are spaced from the sides of the uprights 8 there is no danger of a child being pinched or otherwise hurt by the moving parts of the bob rocker.

What I claim is:

1. A bob rocker comprising rocker-equipped end members, said members including pairs of upright posts, crosstie bars rigidly connecting said posts, upper, lower and intermediate crosstie rods connecting the post 85 of each pair, said upper crosstie rods affording handles, a seat board having bearing blocks journaled on the intermediate crosstie rods, and a foot rack supported on the lower cross- 90 tie rods in parallel arrangement with the seat board, said crosstie bars having notches in which the bearings on the seat board extend to hold said seat board against edgewise shifting movement on the intermediate crosstie rods. 95

2. A bob rocker comprising rocker-equipped end members, said members including pairs of upright posts, crosstie bars rigidly connecting said posts, upper, lower and intermediate crosstie rods connecting the 100 posts of each pair, said upper crosstie rods affording handles, a seat board having bearing blocks journaled on the intermediate crosstie rods, a foot rack supported on the lower cross- 105 tie rods in parallel arrangement with the seat board, and stop blocks on the crosstie bars ar-

ranged to engage the seat board to limit the rocking movement of the end members.

3. A bob rocker comprising rocker-equipped end members, said end members including pairs of upright posts and crosstie rods connecting the posts of each pair and affording handles, a seat board pivotally sup-

ported from the posts with its ends extending outwardly to form seat portions, and a foot rack pivotally supported from the posts below the seat board. 10

In testimony whereof I affix my signature.

MERRILL J. HIRE.
